UNITED STATES PATENT OFFICE.

MILTON H. SHOENBERG AND GEORGE J. HENRY, OF SAN FRANCISCO, CALIFORNIA.

ADJUSTABLE ELECTRIC HEATER.

1,393,320.

Specification of Letters Patent. Patented Oct. 11, 1921.

Application filed October 1, 1919. Serial No. 327,710.

To all whom it may concern:

Be it known that we, MILTON H. SHOENBERG and GEORGE J. HENRY, citizens of the United States, and residents of the city and county of San Francisco, State of California, have invented new and useful Improvements in Adjustable Electric Heaters, of which the following is a specification.

Our invention has for its object the providing of an electric heater, having adjustment in the several directions which will make it most useful in service while retaining simplicity of construction, in operation and a high degree of efficiency.

15 By referring to the accompanying drawings the invention will be made clear.

Figure 1. Is a side view of my heater, partly in section.

20 Figs. 2, 3 and 4 are detailed views of the adjustable double joint and electrical connections therethrough.

Throughout the figures the same numerals refer to similar parts.

25 The base or standard is shown by the numeral 1, with which is adjustably mounted the reflector 2, having substantially at its focal point, an electrical resistance or heat element 3. Mounted in front of said heat element is the protective cage 4, preferably 30 consisting of a plurality of wires affixed to a ring 5, and which is engageable under the flange 6 of the reflector 2; the heat element 3 is mounted upon the stem 7, with which is formed the hollow hinge joint 8, and the 35 stem 7 is provided with a hole 9, which may be cored and which passes through tongue 8 of the joint providing a passage way as indicated by the arrows 10, 11, through which electrical connections are to be made in the 40 well known way, through the socket 12 of the heat element 3.

The tongue 8 is provided with a hole 13 so that it may be clamped between the two jaws 14, 15 of the base 1, by the swivel pivot 16 45 and may be locked in any position by the capstan head nut 17. The base 1 is to be cored having an opening therethrough at 17, between jaws 14, 15, so that the circuit as

carried by the cord 18 may be carried up through the opening 17, and follow the 50 course of the arrows 10, 11, through the stem 7 to the socket 12. The stem 7 may be turned as at 19 and have mounted thereon the collar 20, carrying the bracket arm 21 on which is to be mounted the reflector 2. 55

The collar 20 and arm 21 of reflector 2 may be clamped in any of its adjusted positions by the screw 22, the rotary movement of the reflector 2 with the collar 20 being entirely independent of the electrical 60 connections.

We claim:

1. In an electrical heater comprising a reflector and a base member, said base being hollow; a swivel joint having horizontal 65 pivot wheels therein mounted about an opening to the said hollow base and having a linear opening through said swivel, a hollow stem mounted on the swivel and carrying also said reflector and an electrical resistance 70 heat radiating element mounted on the other end of the stem and substantially about the focus of the reflector, an electrical circuit connection through the base the swivel and the stem adapted to energize the said element. 75

2. Apparatus as set forth in claim 1 and a protective wire cage supported from the periphery of the said reflector and inclosing the said element.

3. Apparatus as set forth in claim 1 and 80 means for fixing the reflector and its cage in any of their adjusted positions about the axis of the swivel.

4. Apparatus as set forth in claim 1 85 wherein the reflector is mounted upon the stem by a circular joint whereby the reflector may be rotated into any desired position about the stem.

In testimony whereof, we have hereunto set our hands at San Francisco, California, 90 this 24th day of September 1919.

MILTON H. SHOENBERG.
GEORGE J. HENRY.

In presence of—
P. S. PIDWELL.
